VARYING DIAMETER VERTICAL TUBE
EVAPORATOR

Francis Hegenbarth, Wilkes-Barre, Pa.

Application November 24, 1947, Serial No. 787,668

3 Claims. (Cl. 159—27)

1

The present invention relates to improvements in varying diameter vertical tube evaporator and is applicable generally to sugar vacuum pans, evaporators, calandrias, or other heat-exchange units for the concentration of solutions, for instance sugar or any other chemical solution.

An object of the invention is to provide an improved heat-exchange unit for use in such apparatus which will promote a more thorough and efficient circulation of the sugar or other solution throughout the pan or other container to the end of promoting a more effective and more expeditious evaporation.

The invention has for its further purpose to provide a heat-exchange unit for accomplishing the above described purposes which is simple in construction, involves no mechanical parts for the promulgation of circulation but uses in a general way the thermal effect produced by the special arrangement of the vertical tubes.

With the foregoing and other objects in view, the invention will be more fully described hereinafter and more particularly pointed out in the appended claims.

In the drawings, in which like parts are denoted by the same reference characters throughout the several views,

Figure 1 is a vertical section taken through a form of vacuum pan and steam belt or calandria as constructed in accordance with the present invention;

Figure 2 is a top plan view with parts broken away and showing a part of the heating belt or calandria;

Figure 3 is an enlarged detailed vertical view taken through a portion of the steam belt or calandria;

Figure 4 is a vertical section taken through a form of calandria in which the bottom tube sheet is inclined and the tubes are of progressively shorter lengths toward the downtake; and

Figure 5 is a similar view showing both upper and lower tube sheets inclined in a convergent manner toward the downtake with larger diameter tubes at the center of shorter length and progressing outwardly in length but in diminishing diameter toward the wrapper sheet.

Heretofore in accordance with present practice a steam belt or calandria consists of top and bottom tube sheets 10 and 11, respectively, a large central well 12, and a wrapper sheet 13 of the general diameter of the pan. One or more steam inlets 14 is provided in the wrapper sheet 13 to admit steam or vapor to the interior of the calandria of this description. The top and bot-

2

tom tube sheets 10 and 11 are provided with circular holes into which tubes 15 are expanded extending to the entire height of the calandria. The steam entering this calandria surrounds completely all the tubes contained in the calandria unit.

The vacuum pan usually consists of a spherical-ly or conically shaped bottom 16 upon which rests the calandria, and upon the calandria is placed a 10 cylindrical hollow part called the liquor belt or vapor belt 17.

A dome shaped top part 18 is provided having a separator 19 to retain any carried over globules of the solution which will be drained back into 15 the pan to avoid loss from entrainment.

Heretofore the vertical tubes 15 used in the calandria were usually made of equal diameter. It is a fact that the diameter of the tubes is in the inverse ratio to the velocity with which the 20 solution flows through the inside of the tubes, which inside constitutes the surface transferring heat from the heating steam in the calandria to the solution boiled in the vacuum pan. Therefore a smaller tube will induce the solution to flow 25 at a higher speed through the tube than a tube of larger diameter will do. As a consequence, the solution will be ejected from the tube at the level of the upper tube sheet with much greater force than through larger tubes. I use an arrangement of such heating tubes in the calandria in several concentric zones around the center 30 downtake in which the outermost concentric zone contains the tubes of smallest diameter, gradually augmented in diameter as they approach the center downtake. The smallest tubes 15^a are shown in an outer zone. For illustration and example purposes, a second zone of progressively 35 larger diameter tubes is shown at 15^b and a third inner zone of still larger diameter tubes is indicated at 15^c. While for the purpose of demonstration we have here selected three zones, it will be depending mostly upon the diameter of the vacuum pan how many zones shall be actually employed for the best results. A greater or 40 lesser number of zones or tube diameters may be employed. An arrangement as just described will result in an induced circulation of the boiling liquid in the pan in the sense that the most rapid circulation will be through the smaller tubes 15^a nearest the periphery of the pan, while the circulation velocity will be gradually reduced toward the center of the pan as tubes of larger diameter are used in zones approaching the center down- 45 take. It will be seen that by this means a definite 50 predetermined circulation of the boiling liquid

55

will have to take place from the periphery of the pan towards the center downtake, which constitutes the coolest part of the calandria. The solution will descend through the center downtake into the bottom from where it will re-ascend in the vertical tubes of the calandria. By the means indicated the use of mechanical apparatus for inducing such circulation will be entirely omitted.

Heretofore in the art, vertical or inclined tubes in a calandria were employed, of equal diameter and length, and expanded at their ends into horizontal or inclined tube sheets. The scope of my invention permits the use of either such horizontal parallel tube sheets or tube sheets arranged with their planes at an angle to the horizontal plane of the calandria, as shown in alternate arrangements on Figure 4 and Figure 5. Such arrangements permit the use of the smallest diameter tubes to be of the relatively greatest length and the progressively relatively larger tubes of progressively lesser length, the largest diameter tubes adjoining the center downtake, being of the relatively shortest length. This arrangement assures the most violent upon circulation in the longest tubes of relatively smallest diameter with the velocity of circulation diminishing in the tubes placed in zones approaching the center downtake in proportion to the relative diameters and lengths of the tubes in the various zones and so that the minimum of circulation will occur in the zone nearest the downtake. It is evident that the arrangement shown on Figure 4 can also be made with only the lower tube sheet at the incline shown, with the upper tube sheet in a horizontal position. In the art the bottom parts 16 are usually carried out in a streamline shape as indicated to avoid any large volume of the boiling mass in an inert or stagnant condition within the bottom.

The velocity of the flow of solution through the tubes depends on the diameter of the tube and the length of same. The smaller in diameter and longer such heating tube is the more violent the rifling effect of the discharge and the greater the height to which the liquid is projected or elevated above the top tube sheet. It is evident therefore that the use of small diameter tubes at the periphery and gradually larger sized diameter tubes towards the center downtake or well, all being of the same length, will produce exactly the effect required for the ideal circulation promoting the highest efficiency of heat transfer and evaporation resulting therefrom.

It is customary in the art to provide means for the removal of incondensable gases from the steam space and for this purpose the customary provisions will be made. The same applies to the removal of condensate resulting from the condensation of steam during the process of heating, which will have to be evacuated rapidly in order not to cover and insulate effective heating surfaces.

On the drawings we have indicated diagrammatically by the use of arrows 20, 21 and 22 the comparative height to which the solution is projected from the tubes 15^a, 15^b and 15^c respectively. It will be seen that the arrows 20 ascend to the highest elevation while the arrows 21 of the intermediate zone tubes 15^b ascend to a lesser elevation and the arrows 22 of the largest diameter tubes 15^c in the central zone ascend to a still lower elevation. Consequently the solution as projected from the innermost tubes 15^c will not interfere with the loop of the circulatory system of the intermediate tubes as indicated by the ar-

rows 21 nor with the circulatory system of the outermost tubes 15^a as indicated by the arrows 20. In other words the loops or cycles of the thermal currents of the several zones will take place independently and the larger circulatory loops respectively from the outer zone to the inner zone and the horizontal transfer of the material from the topmost projected movement toward the center of the calandria prior to descent toward the central well or downtake will take place smoothly without mutually interfering.

While there are independent currents issuing from the various respective zones, any difference in density or temperature is made impossible from 15 the intimate mixture occurring during the descent of those currents through the downtake of the pan thus resulting in a fully homogeneous nature of the boiling mass.

While the above represents one mode of construction of such a vacuum pan with the improved calandria, it merely represents the type most commonly used in the art but any similar or equivalent construction or design will be covered by the invention.

25 While I have disclosed herein the best form of the invention known to me at the present time, I desire it to be understood that I reserve the right to make changes and modifications in the herein described embodiment of the invention provided 30 such changes fall within the scope of the following claims.

What I claim is:

1. In a vacuum pan, a steam belt or calandria comprising an outer wrapper sheet having a 35 steam inlet, top and bottom tube sheets, a central downtake, and tubes of varying diameters having their ends expanded into said top and bottom tube sheets, said tubes arranged in substantially concentric zones between the downtake and the 40 wrapper sheet with the larger diameter tubes in the central zones immediately adjoining the downtake and the smaller diameter tubes in the outermost zone adjoining the wrapper sheet and with intermediate sized diameter tubes in zones 45 between said inner and outer zones.

2. In a vacuum pan, a steam belt or calandria comprising an outer wrapper sheet having a steam inlet, top and bottom tube sheets, a central 50 downtake, and tubes of varying diameters and lengths, having their ends expanded into said top and bottom tube sheets, said tubes arranged in substantially concentric zones between the downtake and the wrapper sheet, with the relatively larger diameter and shorter tubes in the central zone immediately adjoining the downtake and the relatively smallest diameter and longest tubes in the outermost zones adjoining the wrapper sheet and with intermediate size tubes in zones between the said innermost and outermost zones.

60 3. In a vacuum pan, a steam belt or calandria comprising an outer wrapper sheet having steam inlets, top and bottom tube sheets, a central 65 downtake, and tubes of varying diameters having their ends extended through said tube sheets, said tube sheets, being apart from one another by the length of said tubes, said central downtake extending partially beyond the bottom tube sheet, said tubes arranged in substantially concentric zones between said downtake and said wrapper 70 sheet with the larger diameter tubes bordering the periphery of said downtake and the smaller diameter tubes in the outermost zone adjacent said wrapper sheet and intermediate sized diameter tubes in concentric zones between said larger and smaller diameter tubes, said tubes being ar-

ranged with their diameter increasing from the wrapper sheet inwardly to the central downtime.
